UNITED STATES PATENT OFFICE

SAMUEL C. CUTLER, OF MURRAY HILL, NEW JERSEY

GAS WASHING APPARATUS

Application filed October 22, 1926. Serial No. 143,387.

This invention relates to gas washing apparatus.

It has heretofore been proposed, in cleansing air or other gases, to pass the gas through a spray of water produced by centrifugal apparatus, and more particularly, such apparatus has been used in the purification and cooling of producer gas. Such gases, however, leave the producer at high temperature and in order properly to eliminate the solid impurities and to bring the gas to a conveniently usable temperature, it has been found necessary in practical operation, to pass the gas through a plurality of such units in sequence, and it has been necessary to employ apparatus of quite large size to handle the volume of gas.

It has heretofore been proposed to accomplish these results by mounting a plurality of centrifugal units, one above the other, with the centrifugal elements driven by a main shaft, the gas passing through the units in succession and being discharged directly from the one unit into the next.

Difficulty has been experienced, however, with such apparatus by reason of the fact that the heavy duty required causes the elements to get out of order or to become clogged, and this has made it necessary occasionally, to shut down the plant to disassemble the apparatus, and repair the trouble.

In accordance with this invention, the apparatus is so constructed that the movable parts of the spray units may be independently repaired without discontinuing the process or disassembling the apparatus.

It is an object of this invention, therefore, to produce a machine which will produce a thorough contact between the liquid and gas, which will handle large quantities of gas in an efficient manner and which may be readily repaired.

The invention accordingly comprises the features of construction, combinations of elements, and arrangement of parts, which will be exemplified in the construction hereinafter set forth and the scope of the application of which will be indicated in the claims.

For a fuller understanding of the nature

and objects of the invention, reference should be had to the following detailed description taken in connection with the accompanying drawings, in which:

Fig. 1 is an elevation of the apparatus embodying this invention. 55

Fig. 2 is a section along the lines 2—2 of Fig. 1.

Fig. 3 is a section along the lines 3—3 of Fig. 1. 60

Fig. 4 is a section along the lines 4—4 of Fig. 1.

Fig. 5 is a vertical section through a single unit of the device shown in Fig. 1, on a plane parallel to the paper as for the second, fourth or sixth stage counting upwardly from the bottom, or perpendicular to the paper as for the third, fifth or seventh stage. 65

Fig. 6 is a section at right angles to Fig. 5.

Fig. 7 is a vertical section through stage 70 one.

In the drawings the letter A comprises a substantially cylindrical, upright section, which, in the particular embodiment illustrated, may be approximately 86 feet high. 75 The fresh gas is taken in at the bottom through a gas inlet marked "In", and passes upward successively through a plurality of washing apparatus, until it is discharged at the top through a discharge orifice "Out". 80

As illustrated, seven such stages or washing apparatus are employed, which are designated by the numerals 1, 2, 3, 4, 5, 6 and 7 respectively, stage one being the bottom stage, and being the one which first encounters the 85 gas to be washed.

These different stages are generally similar, each comprising a centrifugal pump 10 mounted for rotation about a vertical shaft 11, and driven by a motor 12, the pump being so designed as to pick up water from a suitable basin 13 and to discharge the same centrifugally and laterally against the walls of the casing A. A cone deflector 14, attached to the inner walls of the casing, catches the 90 spray after it has reached the walls of the casing, and deflects it inwardly to fall again into the basin 13. As will be seen from Fig. 3, each of the basins 13 has a central circular portion 13a of less diameter than the casing 95 100

but extends laterally on each side as shown at 13b to meet the side of the casing. These extensions are parallel to and directly beneath the tunnels to be hereinafter described.

Each of the basins 13 is so designed as to overflow into the stage next below it, excepting the basins for stages one and three, which discharge directly to waste, as will be hereinafter described. This overflow may be in any convenient manner. As illustrated each overflowing pan has a central opening with an upturned rim, 13d cooperating with this rim is a cylindrical gate 13g, which may telescope within it to raise or lower the effective level of the rim and thereby raise or lower the level of water in the vessel. The overflow from the third stage is discharged to waste through a pipe 17, which may lead to a sump 18. The pan 13c for the first stage, however, is circular and closes the bottom of the casing, and the overflow from it passes into the sump 18 through a trap 19.

Each of the stages is substantially alike and for that purpose only one need be described.

The pump 10 comprises generally, a plurality of concentric members of conical character. As illustrated, five such members are provided, designated generally by the numerals 21 to 25 respectively. These members are held in a spaced relation by suitable brace 26 to form annular passageways between them. This set of cones which is herein referred to as the pump is supported by a spider 27, which is directly carried upon the shaft 11, fitting, as illustrated, upon a conical bearing 28 of the said shaft and being held in place by a nut 29. In this manner, the pump is maintained in rigid alignment with the shaft so long as the nut 29 is held firmly in place, but it may be removed readily when the nut 29 is removed.

The upper edges of the members 21 to 25 rest in different horizontal planes. As illustrated, each terminates short of the one above it, so that as the cones are rotated to spray water from their upper edges, as will be hereinafter described, each separate conical member forms a separate spray in a plane parallel to, but spaced from that of each of the other members, so that, with the five cones, five separate planes of spray are provided. The passageways 30, between the cones, are open both at the top and bottom, and at the bottom extend below the top edge of the basin 13, so that when the basin is filled with water, the lower end of each of the passageways 30 is submerged. I prefer to make the lower edge 31 of each cone slightly higher than the lower edge of the next interior cone, so as to ensure that at all times each of the passageways 30 shall have a full supply of water.

Each of the shafts 11 is carried by a vertical journal 32, supported by a plate 33, resting upon a circular base 34 which in turn is sup-

ported upon the floor of the tunnel herein-after described. The shaft 11 carries at its upper end a worm wheel 35, keyed to the shaft as shown at 36 and held in place by a nut 37. A thrust ball bearing 38 may be employed to take the weight of the rotating parts, if desired. The plate 33 carries also a journal 39 for a shaft 40, having at one end a worm 41, meshing with the worm wheel 35 and connected to the motor 12, as for example, by a coupling 42. Extending through the casing from side to side at each stage is a tunnel 43 comprising a top 44 and two side walls 45—45, and having its bottom 46 carried by angle bars 47 extending from one side to the other of the casing A. This tunnel is of sufficient width and height to permit the plate 33 to be raised above the base 34 an amount sufficient to enable the pump 10 to be lifted up and carried out of the machine or to be reinserted therein at will. Provision is made for centrally supporting the members 47 by a pair of vertically disposed angles 49 adjacent each wall 45, dependant from cross members 50 at the top of the tunnel. The lower or supporting ends of the angles 49 are terminated by brackets 51 which in turn carry an extended portion 52 of the tunnel floor. The motor 12 is mounted at the floor level within a channel shape base member 48, its opposite ends carried by the members 47—47.

With the above construction, the fresh gas, as shown in Fig. 7, comes in laterally from the gas entrance. It passes through the sheet of water falling from the lower edge of the lower cone deflector 14, and thence passing upwardly between the inner opening of the said cone and the pump, passes through the plurality of laterally directed sprays issuing from the periphery of each of the conical members. The gas thence passes upwardly to the side of the basin 13 of the next stage, inwardly through the sheet of water falling from the cone 14 and again through the sprays of the second stage. In this manner, the gases come into thorough contact with the water, giving up their excess heat and being freed of their impurities.

It will be noted from the description as given that fresh water passes into the second stage, falling from thence into the first, the apparatus is so arranged by reason of the fact that the first and second stages encounter the hottest and at the same time, the most contaminated portion of the gas, and contact with the gas throughout these two stages is sufficient to contaminate the water and to heat it to the maximum point desirable. In the upper five stages, however, the water is passed continuously from each stage to the next, the hottest water encountering the hottest gases in the third stage, while the gases about to exit from the machine and purified to a large extent, then encounter the cleanest and coldest water.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention, which, as a matter of language might be said to fall therebetween.

Having described my invention, what I claim as new and desire to secure by Letters Patent is the following:

1. An air washer comprising in combination, a casing, a plurality of spraying devices within said casing, each having a separate support, means having an access opening to each of said spraying devices, adapted to be closed by the support.

2. An air washer comprising in combination, a vertical casing, a plurality of spraying devices, disposed one above another, within said casing, each having a separate support, means having an access opening to each of said spraying devices, adapted to be closed by the support.

3. An air washer comprising in combination, a casing, a plurality of spraying devices within said casing, each being separately motivated and having a separate support, means having an access opening to each of said spraying devices, adapted to be closed by the support.

4. An air washer comprising in combination, a vertical casing, a plurality of spraying devices disposed one above another within said casing each being separately motivated and having a separate support, means having an access opening to each of said spraying devices adapted to be closed by the support.

5. An air washer comprising in combination a vertical casing, a plurality of horizontal tunnels through said casing each having a horizontal support with an opening therethrough, a self contained spraying device adapted for insertion in the opening of each of said tunnels, insertable through the tunnel and adapted to rest upon said support.

6. An air washer comprising in combination, a vertical casing a plurality of horizontal tunnels through said casing each having a top, and side walls and a horizontal support at the bottom said support having an opening therethrough, a self contained spraying device adapted for insertion in the opening of each of said tunnels, insertable through the tunnel and adapted to rest upon said support and adapted to close said opening.

7. An air washer comprising in combination, a vertical casing, a plurality of horizontal tunnels through said casing each having a horizontal support with an opening therethin, a self contained spraying device adapted for insertion in the opening of each of said tunnels, each including an electric motor and a cone pump, insertable through the tunnel and adapted to rest upon said support.

8. An air washer comprising a vertical casing, a plurality of spraying devices superposed one above another in said casing each of said spraying devices being removable from the casing without necessitating disassembly of other apparatus therein, means for introducing fresh water to certain of said spraying devices, means for supplying other of said devices by water discharged from said first mentioned devices, and means for passing air through said casing in a direction to first encounter the sprays employing reused water, and finally to encounter sprays employing fresh water.

9. An air washer comprising a vertical casing, a plurality of sets of spraying devices in said casing superposed one above another, each of said devices being removable without disturbing the position of the others, means for introducing fresh water to one washer of each set, means for supplying water to other washers of a set by water discharged from the fresh water washer, and means for passing air through said casing in a direction to last encounter said fresh water washer.

10. A gas washer comprising in combination a vertical casing, a plurality of horizontal tunnels through said casing each having a horizontal support, said support having an opening therethrough, a self contained centrifugal spraying device adapted for insertion in the opening of each of said tunnels insertable through said tunnel and adapted to rest upon said support, a sump pan below each of said spraying devices of less diameter in part than said casing, and an annular deflector attached to the inner wall of the casing above and spaced from each of said pans, and below the discharge of the related spraying device, and having an inner diameter less than the outer diameter of said pan.

11. A gas washer comprising in combination a vertical casing, a plurality of horizontal tunnels through said casing each having a horizontal support, said support having an opening therethrough, a self contained centrifugal spraying device adapted for insertion in the opening of each of said tunnels insertable through said tunnel and adapted to rest upon said support, a sump pan below each of said spraying devices of less diameter in part than said casing, and an annular deflector attached to the inner wall of the casing above and spaced from each of said pans, and below the discharge

of the related spraying device, and having an inner diameter less than the outer diameter of said pan, certain of said pans having overflow openings of adjustable height, and means operable from the tunnel below for adjusting said height.

12. A gas washer comprising in combination a vertical casing, a plurality of horizontal tunnels through said casing each having a horizontal support said support having an opening therethrough, a self contained centrifugal spraying device adapted for insertion in the opening of each of said tunnels insertable through said tunnel and adapted to rest upon said support, a sump pan below each of said spraying devices of less diameter in part than said casing, and an annular deflector attached to the inner wall of the casing above and spaced from each of said pans, and below the discharge of the related spraying device, and having an inner diameter less than the outer diameter of said pan, certain of said pans having central overflow openings having upturned rims, and cooperating sleeves for adjusting the overflow height, and means operable from the tunnel below for operating said sleeve.

13. A gas washer comprising in combination a vertical casing, a plurality of horizontal tunnels through said casing each having a horizontal support, said support having an opening therethrough, a self contained centrifugal spraying device adapted for insertion in the opening of each of said tunnels insertable through said tunnel and adapted to rest upon said support, a sump pan below each of said spraying devices of less diameter in part than said casing, and an annular deflector attached to the inner wall of the casing above and spaced from each of said pans and below the discharge of the related spraying device, and having an inner diameter less than the outer diameter of said pan, certain of said pans having central overflow openings having up-turned rims, and cooperating sleeves for adjusting the overflow height, means for operating said sleeve and means for receiving said overflow and conducting it to the side of the next lower tunnel and discharging it into the next lower sump pan.

14. A gas washer comprising in combination a vertical casing, a plurality of horizontal tunnels through said casing each having a top and side walls, and a horizontal support, said support having an opening therethrough, a self contained centrifugal spraying device adapted for insertion in the opening of each of said tunnels insertable through said tunnel and adapted to rest upon said support, and adapted to close said tunnel to the interior of the casing, a sump pan below each of said spraying devices of less diameter in part than said casing, and an annular deflector attached to the inner wall of the

casing above and spaced from each of said pans, and below the discharge of the related spraying device, and having an inner diameter less than the outer diameter of said pan, certain of said pans having central overflow openings having upturned rims, and cooperating sleeves for adjusting the overflow height, and means operable from the next lower tunnel for operating said sleeve.

15. A gas washer comprising in combination a vertical casing, a plurality of horizontal tunnels through said casing each having a top and side walls, and a horizontal support, said support having an opening therethrough, a self contained centrifugal spraying device adapted for insertion in the opening of each of said tunnels insertable through said tunnel and adapted to rest upon said support, and adapted to close said tunnel to the interior of the casing, a sump pan below each of said spraying devices of less diameter in part than said casing, and an annular deflector attached to the inner wall of the casing above and spaced from each of said pans, and below the discharge of the related spraying device, and having an inner diameter less than the outer diameter of said pan, certain of said pans having central overflow openings having upturned rims, and cooperating sleeves for adjusting the overflow height, and means operable from the tunnel for operating said sleeve and means for receiving said overflow and conducting it to the side of the next lower tunnel and discharging it into the next lower sump pan.

16. A gas washer comprising in combination a vertical casing, a plurality of horizontal tunnels through said casing each having a horizontal support, said support having an opening therethrough, a self contained centrifugal spraying device adapted for insertion in the opening of each of said tunnels insertable through said tunnel and adapted to rest upon said support, comprising a pumping element rotating on a vertical shaft, and a driving motor operating on a horizontal shaft, a sump pan below each of said spraying devices of less diameter in part than said casing, and an annular deflector attached to the inner wall of the casing above and spaced from each of said pans, and below the discharge of the related spraying device, and having an inner diameter less than the outer diameter of said pan.

17. An air washer comprising in combination, a casing, a centrifugal vaporizer mounted on a vertical shaft within said vaporizer, said vaporizer being adapted to be removed from the washer without disassembly, a sump pan within said casing of less diameter in part than said casing to afford a passage for air between said casing and said pan, and an annular deflector carried by said casing extending inwardly from said casing above and

- spaced from said pan, and below the discharge of said vaporizer said deflector having an inner diameter less than the outer diameter of said pan.
- 5 18. An air washer comprising in combination, a casing, a centrifugal vaporizer mounted on a vertical shaft within said vaporizer, said vaporizer being adapted to be removed from the washer without disassembly, a sump pan within said casing of less diameter in part than said casing to afford a passage for air between said casing and said pan, and an annular deflector carried by said casing extending inwardly from said casing above and spaced from said pan, and below the discharge of said vaporizer said deflector having an inner diameter less than the outer diameter of said pan, said pan having an overflow opening and means for altering the level of said liquid.
- 10 19. Apparatus for treating gases which includes a tower having gas treating compartments, a liquid spraying and recirculating device suspended within each gas compartment, means disposed outside of each gas compartment for supporting the said device, and means to actuate each device independently of the remaining devices.
- 15 20. Apparatus for treating gases which includes a tower having vertically spaced gas-treating compartments and having work passages extending transversely of the tower between adjacent gas-treating compartments, and gas passages disposed within the tower and at the sides of the work passages for interconnecting adjacent compartments for the passage of gas successively through a plurality of compartments.
- 20 21. Apparatus for treating gases which comprises a tower having a plurality of interconnected gas-treating compartments spaced vertically apart from each other, and having also a plurality of work passages extending transversely of the tower between the gas-treating compartments, a liquid spray forming device within each compartment and accessible from the adjacent work passage and means for actuating the devices.
- 25 22. Apparatus for treating gases which comprises a tower having a plurality of interconnected gas-treating compartments spaced vertically apart from each other and having also a plurality of work passages extending transversely of the tower between the gas compartments, a liquid spray forming device within each compartment, means in the work passage above each said device for suspending the same within its compartment, and means for actuating the devices.
- 30 23. Apparatus for treating gases which comprises a tower having a plurality of interconnected gas-treating compartments spaced vertically apart from each other and having also a plurality of work passages extending transversely of the tower between the gas compartments, each work passage having an opening through the floor thereof into the gas-compartment therebeneath, a spray device removable through each said opening, means in the work passage for suspending the device within the compartment therebeneath, and means for actuating each device independently of the other devices.
- 35 24. Apparatus for treating gases which comprises a tower having a plurality of interconnected gas-treating compartments spaced vertically apart from each other, and having also a plurality of work passages extending transversely of the tower between the gas compartments, each work passage having an opening through the floor thereof into the gas-treating compartment therebeneath, a spray device removable through each said opening, means in the work passage for suspending the device within the compartment therebeneath, and means in the work passages for actuating each device independently of the other devices.
- 40 25. Apparatus for treating gases which comprises a tower having a plurality of interconnected gas-treating compartments spaced vertically apart from each other, and having also a plurality of work passages extending transversely of the tower between the gas compartments, each work passage having an opening through the floor thereof into the gas-treating compartment therebeneath, a spray device removable through each said opening, and means in the work passages for removing the devices from the compartments.
- 45 26. Apparatus for treating gases which comprises a tower through which gases may flow and having a plurality of work passages extending transversely of the tower, each work passage having an opening therefrom into the interior of said tower, a spray forming device associated with and removable through the said opening, and means in each work passage for supporting said spray forming device within the tower.
- 50 27. Apparatus for treating gases which includes a tower having gas treating compartments, work passages extending transversely of the tower between adjacent gas compartments, independent liquid spray forming units supported in the passages and each extending into an adjacent gas compartment, and means for actuating the devices independently of each other.
- 55 28. Apparatus for treating gases which includes a tower having gas treating compartments, work passages extending transversely of the tower between adjacent gas compartments, and independent spray-forming units supported from the passages, each unit comprising a spray-forming device extending into and disposed to spray liquid in a gas compartment, and actuating means for each device disposed in the adjacent work passage.
- 60 29. Apparatus for treating gases which

- includes a tower having gas treating compartments, work passages extending transversely of the tower between adjacent gas compartments, and independent spray-forming units supported from the passages, each unit comprising a spray-forming device extending into a gas compartment, and means disposed in the work passages for supporting the devices independently of each other.
30. Apparatus for treating gases which includes a tower having gas treating compartments, work passages extending transversely of the tower between adjacent gas compartments, and independent spray-forming units in the compartments, each unit being supported in a work passage independently of each other and actuated independently of each other.
31. Apparatus for treating gases which comprises a tower having a plurality of vertically arranged interconnected gas treating compartments, movable spray forming devices in the compartments, work passages each extending transversely of the tower between adjacent compartments in proximity to the devices therein and having a normally closed opening for access to the device in one of the adjacent compartments, and means for actuating the spray forming devices.
32. Apparatus for treating gases which comprises a tower having a plurality of vertically arranged interconnected gas treating compartments, rotary spray forming device in the compartments, bearing means operatively associated with and disposed adjacent to each device, work passages each extending transversely of the tower between adjacent compartments and in proximity to the device and bearing means in one of the adjacent compartments, and having a normally closed opening for access to the said bearing means, and means for actuating the spray forming devices.
33. Apparatus for treating gases which comprises a tower having a plurality of vertically arranged interconnected gas treating compartments, a plurality of rotatable spray forming devices in the compartments, bearing means operatively associated with and disposed adjacent to the said devices, work passages each extending transversely of the tower between adjacent compartments and in proximity to the devices therein and their bearing means, the said work passages having means for permitting access therefrom to the adjacent spray forming devices and their bearing means, and means for rotating the said devices.
34. Apparatus for treating gases which comprises a tower having a plurality of vertically arranged interconnected gas treating compartments, a plurality of rotatable spray forming pumps in the compartments, individual bearing means each operatively associated with one of the said pumps and dis-

posed adjacent thereto, a plurality of work passages each extending transversely of the tower between adjacent compartments and in proximity to the adjacent pumps and bearing means, means in the work passages for permitting access to the bearing means of the pump adjacent thereto, and a power shaft operatively associated with the pumps to rotate the same.

In testimony whereof I affix my signature.
